SCAFFOLDING AND APPARATUS THEREFOR

Henry Sway, Cincinnati, Ohio

Application September 17, 1940, Serial No. 357,138

4 Claims. (Cl. 304—15)

This invention relates to scaffolding.

An object of the present invention is to provide scaffolding which is adapted to be suspended beneath horizontal surfaces, such as ceilings, and the like, or which is adapted to be suspended against vertical surfaces, such as walls and the like.

Another object of the present invention is to provide improved anchorage means for securely engaging elevated load sustaining members from which the scaffolding is suspended.

A further object of the invention is to provide three basic structural units from which any type of suspended scaffolding may be quickly and inexpensively fabricated.

Still another object of the invention is to provide improved fully suspended scaffolding which eliminates entirely the need for cumbersome and expensive scaffold structures built up from the ground or other supporting surfaces.

Still another object of the invention is to provide suspended wall scaffolding which comprises a plurality of identical basic units, adapted to be hung one from another whereby to provide a plurality of parallel vertically spaced work levels or platforms.

Still a further object of the invention is to provide fully suspended wall scaffolding embodying means for shifting each work platform towards and against the outer surface of the vertical wall against which the scaffolding is hung.

Still a further object of the invention is to provide improved anchorage means for positively engaging elevated load sustaining members such as I beams and the like.

A further object of the invention is to provide improved anchorage means for engaging overhanging load supporting ledges and the like without becoming overbalanced under load.

Still a further object of the invention is to provide suspended scaffolding, the component parts of which are structurally strong, yet simple in structure and inexpensive in cost.

These and other objects are attained by the means described herein, and disclosed in the accompanying drawings, in which.

Fig. 1 is a side elevational view of a wall scaffold embodying the teachings of the present invention, suspended against a vertical wall from an overhanging, load-sustaining member, to wit, the gutter.

Fig. 2 is a side elevational view showing two basic hanger units which comprise a detail of the invention, suspended one from the other.

Fig. 3 is a side elevational view of a so-called ceiling hanger, as contrasted from the wall hangers of Fig. 2.

Fig. 4 is a front elevational view of my improved anchorage means in the form of a hanger hook or a pair of hanger tongs comprising a detail of

the invention, operatively associated with a horizontal load support member in the form of an I beam.

Fig. 5 is a side elevational view of one of the legs of the pair of hanger tongs of Fig. 4, operatively associated with an overhanging load sustaining member.

Fig. 6 is a side elevational view of a pair of bridge-beam tong hooks, which comprise a detail of the invention, operatively associated with the lower flange of a bridge I beam.

With reference to Fig. 1, it will be noted that the scaffolding of the present invention comprises broadly speaking, anchorage or support-surface-engaging means 10 and hanger means 11 suspended therefrom. Suitable platform forming material, such as a board 12 is adapted to engage and be supported between a pair of spaced hangers 11, as shown.

With reference to Fig. 2, it will be noted that hanger means 11, hereinafter referred to as a wall hanger or wall stirrup 11, as contrasted with the ceiling hanger or stirrup 13 of Fig. 3, comprises a shank portion 14, the upper end of which terminates in an attachment member 15 and the lower end of which terminates in a closed loop 16. In the preferred embodiment of the invention, the wall hangers 11 as well as the ceiling hangers 13 are fabricated from a single length of rod stock, such as cold rolled steel or the like, whereby to provide a unitary one piece hanger.

The closed loops 16 of the hangers of Figs. 2 and 3, comprise a bottom element 17, a front element 18, a rear element 19 and a pair of upwardly convergent top elements 20. A scaffold board, denoted generally by the numeral 12 is adopted to be introduced, end first, through loop 16 of each of a pair of spaced hangers so as to rest upon bottom element 17 between the front and rear elements 18 and 19, as shown.

The primary distinction between wall hangers 11 and ceiling hangers 13 is that each wall hanger is provided with means for permitting another hanger to be suspended from its bottom element, as disclosed in Fig. 2, thereby making it possible to provide a plurality of work levels, one below another on the face of a vertical wall. Said means may comprise a U-shaped auxiliary load bearing loop 22 provided in bottom element 17. In the preferred embodiment of the invention, front element 18 of loop 16 comprises one leg of said U-shaped auxiliary loop 22 in order that any undue stresses induced in said auxiliary loop by a load applied thereto will be divided between front element 18 and bottom element 17, instead of being concentrated or localized on bottom 17 as would be the case were the auxiliary loop 22 provided entirely in bottom 17 intermediate the front and rear elements 18 and 19.

With reference to Fig. 2, it will be noted that

the attachment member of the lowermost wall hanger, denoted by the letter B, engages and is entirely suspended from the auxiliary loop 22 of hanger A. It will likewise be noted that the vertical axis through the center of shank 14, of the lower hanger B is shifted to the left of the vertical axis of the upper hanger A, by an amount equal to the lateral distance between the vertical axis of shank 14 and the vertical axis of its auxiliary loop 22. Such construction results in the front element 18 of the lower hanger B being positively shifted against the outer face C of vertical wall 31, thereby precluding accidental and/or unintentional shifting of the work platform upon which the operators are supported, 15 away from said wall.

In actual practice, the lower wall hanger B will assume the position indicated by dotted lines relative to upper hanger A and wall 31. It will be noted that the upper portion of front element 18 of the lowermost hanger is thus positively shifted towards and actually engages the outer face C of wall 31 at point D.

If desired, another wall hanger may be hung from auxiliary loop 22 of the lower hanger B, and so on until the entire side wall C has been provided with scaffolding. It will be observed that the completed wall scaffold comprises a plurality of so-called basic units, each of which comprises a pair of wall hangers 11 and a scaffold board 12.

It should likewise be observed that inasmuch as each lower wall hanger is suspended from the auxiliary loop of the next higher wall hanger, the necessity for braced reinforcements and for scaffolding erected from the ground up, is effectively eliminated.

By reason of the inter-relationship between the attachment member 15 of a lower wall hanger and the auxiliary loop 22 of the next higher wall hanger, a pivotal connection is provided which enables the lower wall hanger to be freely shifted to the right or to the left of a vertical dropped from the center of loop 22. Such pivotal connection permits suspended scaffolding to be erected against surfaces which are inclined or curved away from a vertical, such as by way of example, the hull of a ship. This may be expeditiously accomplished by drawing the closed loop portion 16 of each hanger against the hull of the ship by means of ropes, cables, or the like. In order to provide safety means to prevent operators from falling from the rear side of the scaffolding, a railing support 50 may be secured to each wall hanger. Such a support may comprise a length of rod-like stock bent to provide one or more loops such as 23 and 24 through which lengths of boarding, pipe, cable, rope or the like may be threaded. Opposite ends of the rod may be secured to shank 14 and to the rear element 19 of the closed loop 16 by means of spot welding, or the like.

The ceiling hanger of Fig. 3, may, if desired, be provided with a safety rail on both sides of shank 14.

The anchorage, or support-surface-engaging means 10 may comprise a one-piece hanger hook including a hook-shaped upper portion or jaw 26 and a body portion 28, the lower end of which terminates in a load bearing eyelet 27.

As illustrated in Fig. 1, the point or load-bearing tip 28 of jaw 26 engages the bottom 29 of a gutter 30, or other overhanging support member, at a point disposed in substantial alignment with the plane of outer face C of vertical wall

31. The body portion 26 of the hook extends forwardly of, that is, to the left of a straight line x—x, which extends from the load bearing tip 28 through the center of the load bearing eyelet 27 so as to provide a wall engaging face 32, which is adapted to abut against wall 31 at E. By reason of such construction, the vertical component of a load applied to eyelet 27 causes the hanger hook to snugly abut wall 31 as eyelet 27 seeks to become vertically aligned below tip 28. In this manner, the lower portion 32 of hook 10 normally bears against the outer face of the wall, thereby effectively eliminating all danger of the hook becoming overbalanced under load.

With reference to Fig. 5, it will be noted that if desired a hole 34 may be provided in the hook or jaw portion 25 of hanger hook 10, through which a rope 35, cable or the like may be passed for the purpose of securing or anchoring said hook against accidental or unintentional outward disengagement from gutter 30. Such eyelet likewise provides attachment means through which a rope, or the like, may be passed to facilitate hoisting of the hanger hook from the ground up to the overhanging load bearing support member.

In these instances where it is desirable or necessary to suspend the ceiling hanger of Fig. 3 from a horizontal load-sustaining member such as a beam or the like, the tongs of Fig. 4 are particularly useful. These tongs comprise a pair of identical or corresponding hanger hooks 10, which are turned relative to one another so as to provide a left and a right hook pivotally interconnected by means of a bolt 36 which passes through aligned bolt holes 37 provided one through the body portion 26 of each hook member intermediate eyelet 27 and jaw 25.

It should be noted that the centers of the bolt holes 37 are on a straight line F—F passed through the center of the load bearing eyelet 27 and on the center of web 38 of I beam 39 with which said tongs are adapted to be associated. By reason of this relationship it is seen that eyelets 27 of the pivotally joined hooks 10 are disposed in register only when the load bearing tips 28 are spaced apart by a distance approximately equal to the width of the web of I beam 39. It has been found that by causing the eyelets 27 to register when the lateral distance between hook tips 28 is five-eighths of an inch for a jaw having a radius of three inches, such a pair of tongs will accommodate standard I beams having a flange width up to and including six inches.

In the preferred embodiment of the invention, a small hole 41, having its center on line F—F, is provided through each of the hook or tong leg members 10, between bolt holes 37 and eyelets 27.

After the tips 25 of the respective jaws of a pair of tongs have been closed over the upper face of the lower flange of an I beam, a pin, nail, or the like, may be passed through the aligned holes 41 whereby to positively, though temporarily, lock the jaws of the tongs to the I beam until the attachment member 15 of a hanger can be introduced through the aligned and registered load bearing eyelets 27. It is preferable, though not absolutely necessary, to withdraw the temporary locking means from holes 41 after the hangers have been suspended from the registered eyelets 27, in order to have but one jaw locking means operative. In those instances where the eyelets 27 are not in complete register, the greater the load applied to said eyelets by means of a hanger attachment member 15, the

tighter the jaw tips 28 will be drawn together against the web 38, thereby increasing the bond between the tongs and the load sustaining member.

The pair of tongs disclosed in Fig. 6 are fundamentally and structurally similar to the tongs of Fig. 4, being distinguishable therefrom in size only. The tongs of Fig. 6 are particularly adapted for use in large structures such as bridges, and the like, wherein web 138 is from three inches to several feet in width. Those parts of Fig. 6 which correspond to similar parts of Fig. 4 bear the same numerals, raised however, by one hundred. It should be noted that the load bearing eyelets 127 are on a vertical axis F—F' dropped from the center of web 138 and that the pivot bolt 136 passes through the registered pivot holes 137 which are disposed on said vertical axis F—F'. In this manner the load is evenly distributed to each leg of the tongs, whereby the pull on flange 141' on opposite sides of web 138 is equalized.

It should be observed that by using the three basic elements, viz., wall hanger 11, ceiling hanger 13 and a pair of hanger tongs of Fig. 4, it is possible to provide fully-suspended scaffolding of the so-called ceiling or wall type without having to resort to special equipment. When the hooks comprising a pair of hanger tongs are separated, they provide a pair of hanger hooks each of which are adapted to engage an overhanging load bearing support member from which a wall hanger may be suspended without danger of said hook being unbalanced when subjected to load.

It should be noted that in the event a load in excess of the yield point of a hanger hook be applied thereto, the hook cannot become overbalanced and twist about its vertical plane and snap off as occurs when a painter's scaffold hook is over loaded. Hanger hook 10, will under an excess load, merely be drawn downwardly as the loop or jaw portion is straightened out, during which process the body portion 32 will remain in contact with the wall as at point E of Fig. 1. Therefore, it is apparent that even though my hanger hooks be overloaded, they will never become overbalanced.

It should be understood that the hanger tongs of Fig. 4 may be anchored from a wooden beam or rafter by merely drilling a pair of holes in opposite faces thereof to provide a grip for the jaw tips 25.

It should likewise be understood that various modifications and changes in the structural details of the various basic devices may be made, within the scope of the appended claims, without departing from the spirit of the invention.

What is claimed is:

1. The combination with a building wall including an overhanging load sustaining member, of a fully suspended wall scaffold comprising a plurality of similar basic units, each basic unit comprising a pair of wall hangers and a scaffold board, each wall hanger comprising a shank, the upper end of which is provided with an attachment member and the lower end of which is provided with a closed scaffold-board-receptive loop which includes an auxiliary load bearing loop, each auxiliary load bearing loop adapted to receive an attachment member of a hanger of a second basic unit which is secured to and suspended from said first basic unit which

is carried by and suspended from said overhanging load sustaining member.

2. The combination with a building wall including an overhanging load sustaining member, of a fully suspended wall scaffold comprising a plurality of similar basic units suspended one from another, each basic unit comprising a pair of wall hangers and a scaffold board which extends between and is supported by said hangers, each hanger comprising a shank the upper end of which is provided with an attachment member and the lower end of which is provided with a closed scaffold-board-receptive loop which includes bottom, front, rear and top elements, said loop including an auxiliary load bearing loop provided in said bottom element adjacent the front element, said auxiliary loop adapted to receive the attachment member of the hanger of a second basic unit suspended therefrom, and means for securing the attachment members of the uppermost basic unit to said overhanging load sustaining member, the front element of the loop of each suspended hanger adapted to normally abut said wall for maintaining said scaffold boards in close proximity to said wall.

3. As a new article of manufacture, a scaffold hanger fabricated from a single length of rod like stock bent to form a base portion, a pair of upstanding side members disposed at substantial right angles to said base, a pair of top members which converge upwardly from said side members to a common apex and a shank portion extending upwardly from said apex and at substantial right angles to said base, the upper end of said shank being turned upon itself to provide an inverted U-shaped hook the legs of which are in a plane at substantial right angles to the plane of said side members, said base being provided with a U-shaped loop adjacent a side member, wherein one leg of said loop is common with said side member, said loop adapted to receive the hook of a second similar hanger for suspending said second hanger therefrom.

4. As a new article of manufacture, a scaffold hanger fabricated from a single length of rod like stock bent to form a base portion, a pair of upstanding side members disposed at substantial right angles to said base, a pair of top members which converge upwardly from said side members to a common apex and a shank portion extending upwardly from said apex and at substantial right angles to said base, the upper end of said shank being turned upon itself to provide an inverted U-shaped hook the legs of which are in a plane at substantial right angles to the plane of said side members, said base being provided with a U-shaped loop adjacent a side member, wherein one leg of said loop is common with said side member, said loop adapted to receive the hook of a second similar hanger for suspending said second hanger therefrom, and a railing support carried by and secured to said hanger, said railing support comprising a length of rod-like stock bent to an L-shape, the free end of one leg of the L being connected to said shank and the free end of the other leg of said L being secured to that side member remote from said loop, said railing support including means for facilitating the fastening of a rope thereto.

HENRY SWAY.
